UNITED STATES PATENT OFFICE.

MICHAEL P. DAVEN, OF ST. LOUIS, MISSOURI, ASSIGNOR OF ONE-THIRD TO CHARLES W. F. CAMPBELL AND ONE-THIRD TO FRED P. WICHARD, OF ST. LOUIS, MISSOURI.

ATTACHMENT FOR NAILING MACHINES.

Application filed August 29, 1925. Serial No. 53,287.

This invention relates generally to improvements in nailing machines, and particularly to an attachment for an automatic nailing machine adapted to nail lids or covers on boxes and crates.

It is the practice in some manufacturing plants where goods are packed in boxes and crates, for instance, in packing houses, to overfill said boxes and crates so that the contents thereof extend above the top edges of said boxes and crates. This practice renders it rather difficult to nail the lids or covers in place on said boxes and crates, this difficulty being felt particularly in connection with the use of automatic nailing machines which, prior to this invention, were considered unfit for nailing lids or covers on overfilled boxes and crates. To render it possible to employ an automatic nailing machine to nail the lids of overfilled boxes and crates in place thereon, I have devised the attachment disclosed in the present application which is adapted to be attached to an automatic nailing machine, and when so attached will cause the lids or covers of the overfilled boxes being operated on to be forced into their proper positions and held in such positions during the nailing operation.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a side elevation showing a portion of the automatic nailing machine provided with my improved attachment.

Fig. II is a sectional detail taken through my improved attachment showing in cross section the portion of the nailing machine by which the attachment is supported.

Fig. III is a plan view of my improved attachment, portions of the supporting arms thereof being broken away to conserve space.

Fig. IV is an inverted plan view of my

improved attachment, in this view also the supporting arms being broken away.

Fig. V is a view similar to Fig. III, but showing the arrangement when a greater number of spacers is employed.

55

In the drawing, A designates a fragment of an automatic nailing machine which may be of the type usually employed to nail lids or covers on boxes and crates, said machine including a supporting frame B which is provided with a work table C. Arranged above the work table C and adapted to move vertically with relation thereto is a plurality of heads D provided with downwardly movable nail-driving members (not shown). 60 The nails are contained within a hopper (not shown), and said nails are conveyed from said hopper to said heads by means of a plurality of tubes E. In the operation of the machine briefly described above a box or 70 crate is located on the work table C and the lid or cover of said box or crate is arranged in place thereon. The mechanism of the nailing machine is then actuated, thus causing the heads D to be moved downwardly 75 and also causing nails, which have previously been located in the path of travel of the downwardly movable nail-driving members, to be driven through said lid or cover into the walls of the box or crate, whereby said lid or cover is secured in place on said box or crate.

The foregoing briefly describes the operation of nailing the lids or covers on boxes or crates by means of an automatic nailing ma- 85

chine when said boxes or crates are not overfilled. When the boxes or crates are overfilled, however, it has been found to be practically impossible to employ an automatic nailing machine to nail the lids or covers in 90 place on said boxes or crates, for the reason that each of said lids or crates is usually composed of a plurality of resilient strips of wood which are bowed by the upwardly projecting contents of the box or crate when 95 said strips are being secured in place on said box or crate, and to successfully nail said lids in place with an automatic nailing machine it would be necessary for the operator to hold all of the bowed resilient strips mak- 100

ing up the lid during the nailing operation. It was found that the number of strips, together with the resilient nature of said strips, rendered the holding of all of said strips 5 during the nailing operation a very difficult feat, and for this reason automatic nailing machines have been very seldom used for nailing lids on overfilled boxes or crates.

The present invention contemplates a very 10 simple attachment for a nailing machine by the use of which the resilient strips of wood which comprise the lid of a box or crate may be very positively drawn into their proper positions when said box or crate is being 15 located in place on the work table of the machine and held in such positions during the operation of nailing said strips to the body portion of the box or crate.

The automatic nailing machine A illustrated in the drawing is provided with a bar F which extends transversely of said machine at the front thereof, said bar being located immediately adjacent to the heads D and being provided with an inverted T-shaped slot F' which extends longitudinally of said bar from end to end thereof. Every automatic nailing machine of the type illustrated in Fig. I is provided with one of the bars F, said bars being the means for supporting the heads D, and I utilize this bar as the supporting means for my attachment, which will now be described.

1 designates a plate which is arranged immediately above the work table C of the nailing machine A, as shown in Fig. I, the longitudinal dimension of said plate being parallel with the forward face of the nailing machine and said plate being so arranged that it is inclined from front to back with 20 respect to the work table C, with the forward edge of said plate in a higher plane than the rearmost edge thereof. The plate 1 is supported by means of arms 2 which are secured at ends thereof to said plate, as 25 shown in Figs. III, IV and V, the ends of said arms 2 opposite to the ends thereof which are secured to the plate 1 being arranged immediately above the bar F. 3 designates bolts, one of which is extended 30 through each individual arm 2 at the end thereof adjacent to the bar F. The bolts 3 are each provided with an enlarged head portion 3', which is located within the enlarged portion of the T-shaped slot F' formed in the bar F, and each of said bolts includes a threaded shank portion which extends through an opening in the associated arm 2. 4 designates wing nuts which are screwed on the threaded shank portions of 40 the bolts 3 and which are adapted to bear against the top faces of the arms 2. From the foregoing it is plain that when the wing nuts 4 are screwed tightly against the top faces of the arms 2 said arms will be securely fixed to the bar F, due to the fact that

the enlarged head portions 3' of the bolts 3 will be drawn upwardly into firm frictional contact with the adjacent portions of the bar F, and the end portions of the arms 2 will be forced downwardly into firm frictional contact with the top face of said bar F.

As stated before in this specification, lids and covers of boxes and crates often comprise each merely a plurality of resilient strips of wood spaced apart from each other which extend longitudinally or transversely of the box or crate, as shown in Fig. III and designated by the reference character 5. These strips of wood are entirely independent of each other, and it is important that said strips be properly spaced before they are nailed in place on the boxes or crates. I therefore arrange spacers 6 on the lower face of the plate 1, said spacers being adapted to function as guides which will properly position the strips of wood 5 prior to the nailing operation. The spacers 6 comprise each a block of material which extends downwardly from the lower face of the plate 1, and said block of material is provided with one or more bolts or similar fastening devices 7 which pass through openings 8 in the plate 1 and receive wing nuts 9, whereby said block of material is secured to said plate 1. The openings 8 in the plate 1 through which the bolts 7 pass are elongated, as shown in Figs. III, IV and V, so that the spacers 6 may be adjusted longitudinally of the plate to provide for strips of wood of different widths. By referring to Figs. III and IV, which show plates provided with three spacers, it will be noted that the outer spacers are arranged so that their side faces are at an angle to the side faces of the intermediate spacer. It will also be noted that the intermediate spacer is provided with a pointed forward end portion. This arrangement is intended to provide for the proper and easy introduction of the strips of wood 5 between the spacers 6 and reduces the likelihood that said strips of wood will abut against ends of the spacers 6 and be stopped thereby.

In Figs. III and IV three spacers 6 are shown, while in Fig. V four spacers are shown. The arrangement of the spacers in Fig. V is intended for use where the lid or cover being nailed is composed of three strips of wood, instead of two as would be the case when the spacer arrangement shown in Figs. III and IV is employed. It will be noted from Figs. III and IV that in addition to the elongated openings 8 through which the bolts 7 pass two additional elongated openings 8' are illustrated. When the lid or cover being nailed is composed of two strips of wood the bolts 7 associated with the spacers 6 are passed through the elongated openings 8, when said spacers

will be arranged as shown in Figs. III and IV. However, when the lid or cover being nailed is composed of three strips of wood, instead of having one spacer at the approximate center of the plate 1, as shown in Figs. III and IV, a pair of intermediate spacers is employed and the bolts 7 associated with said intermediate spacers are extended through the elongated openings 8', as shown in Fig. V. It is apparent, therefore, that the spacers 6 of my improved attachment are adjustable longitudinally of the plate 1 to provide for strips of wood of different widths, and also said plate 1 is provided with elongated openings so located that a greater or less number of spacers may be employed to guide a greater or less number of strips of wood.

In the operation of an automatic nailing machine provided with my improved attachment, an overfilled box is located on the work table C of said nailing machine with an end of said box under the heads D. The strips of wood which compose the lid or cover of said box are then introduced under the plate 1 and between the spacers 6, and when the end portions of said strips of wood are properly positioned above the wall of the box to which they are to be secured, the nailing machine is actuated and said strips are nailed to said box. In the case of an overfilled box there is no difficulty in nailing the strips which compose the lid at one end only of the box, as the difficulty does not arise until the strips of wood have been nailed to the box at one end thereof and an attempt is made to nail the other ends of said strips to said box. When the strips of wood are nailed to the overfilled box at one end thereof the intermediate portions of said strips rest on the upwardly projecting contents of the box, thus causing the strips of wood to incline upwardly as suggested by dotted lines in Fig. I. Heretofore it would be necessary for the operator of the automatic nailing machine to force the strips of wood downwardly with his hands until the ends thereof could be introduced beneath the heads D of the nailing machine, and it would be necessary also for the operator to properly space the strips of wood relative to each other and hold them in their proper positions while the nailing operation was taking place. When the nailing machine is provided with my improved attachment, however, it is only necessary for the operator to draw the box rearwardly on the work table C and reverse said box after the strips of wood have been nailed at one end of the box. The box is then moved inwardly on the work table toward the nailing mechanism, and as this movement takes place the loose ends of the upwardly inclined strips of wood will contact with the lower face of the plate 1, and as said movement of the box

continues said strips of wood will be cammed downwardly until the ends thereof contact with the top edges of the wall of the box to which said strips of wood are to be nailed. When the strips of wood are positioned as 70 described, the nailing mechanism is actuated and nails are driven through the strips of wood into the wall of the box.

When the box is being moved inwardly on the work table C as already described, 75 the strips of wood of which the lid is composed pass between the spacers 6 whereby said strips of wood are properly spaced relative to each other.

While I have described the spacers 6 as 80 being intended for use particularly in spacing the strips of wood which compose the lid of a box, it is to be understood that said spacers may be used when the body portion of the box is being made to space 85 the strips of wood when the walls of said body portion are composed of strips of wood spaced apart from each other.

I claim:

1. An attachment for a box-nailing machine having a work table, comprising a member arranged above said work table against which lids of boxes are moved to force said lids into contact with the body portions of the boxes during the operation 90 of nailing said lids on said boxes, and spacers on said member adapted to space and position the strips of material of which said lids are composed. 95

2. An attachment for a box-nailing machine having a work table, comprising a member arranged above said work table against which lids of boxes are moved to force said lids into contact with the body portions of the boxes during the operation 100 of nailing said lids on said boxes, and spacers on said member adapted to space and position the strips of material of which said lids are composed, said spacers being 105 adjustable relative to said member. 110

3. An attachment for a box-nailing machine having a work table, comprising an inclined plate arranged above said work table against which lids of boxes are moved to force said lids into contact with the body portions of the boxes during the operation 115 of nailing said lids on said boxes, elongated openings formed through said inclined plate, spacers on said inclined plate, said spacers being provided with members adapted to be passed through said elongated openings whereby said spacers may be adjusted relative to said plate, and means whereby said spacers may be retained in fixed positions 120 on said plate. 125

4. An attachment for a box-nailing machine having a work table, comprising an inclined plate arranged above said work table against which lids of boxes are moved to force said lids into contact with the body 130

portions of the boxes during the operation of nailing said lids on said boxes, a plurality of openings formed through said plate, a plurality of spacers having members associated therewith adapted to be extended through said openings, and means whereby said spacers are retained in fixed positions on said plate, said spacers being so shaped

and positioned that tapering guideways are formed therebetween into which the strips of material of which the lids are composed are introduced to properly space and position said strips of material.

In testimony that I claim the foregoing I hereunto affix my signature.

MICHAEL P. DAVEN.
